UNITED STATES PATENT OFFICE

CHRISTIAN COUPARD, OF PARIS, FRANCE, ASSIGNOR TO SOCIETE ANONYME "L'ASPIRATION SCIENTIFIQUE," OF PARIS, FRANCE

SECONDARY FLUID CURRENT PRODUCTION APPARATUS

Application filed March 9, 1928, Serial No. 260,412, and in Belgium August 6, 1927.

The present invention relates to improvements in systems for utilizing the dynamic effect of a main fluid current for increasing the velocity of a secondary or derived fluid current and, more particularly, to improved ventilating systems adapted to be applied to chimneys and the like.

One of the objects of the invention is to provide a novel type of draft producing device of special form and dimensions, the latter being so chosen as to utilize to a maximum the dynamic effect of fluid currents exterior thereto.

Other objects will appear in the course of the detailed description now to be given in connection with the accompanying drawings, in which:—

Fig. 1 shows, in elevation, a first constructive embodiment of the invention;

Fig. 2 represents an elevation of a second form of the invention;

Fig. 3 is an elevation of a third form of the invention;

Fig. 4 illustrates in elevation a form of device having a plurality of smoke outlets;

Fig. 5 is an elevation of a structure designed to increase the velocity of a propeller positioned in an air current;

Figs. 6 to 8 are a series of elevations showing the invention as applied respectively to the ventilation of a house and of an automobile and to prevent the extinguishing of a lantern;

Fig. 9 is a diagram showing the effective draft produced in a chimney by a device constructed in accordance with the invention under varying operating conditions.

In the various figures of the drawing the main fluid current is represented by a solid arrow while the secondary fluid current, i. e. the one resulting from the dynamic effect of the main current, is represented by an arrow in dotted lines.

a represents a pipe in which it is desired to produce a draft, said pipe being formed in the shape of a cylinder or of a cone having its generatrix inclined at substantially 7° to its axis,—*b*, a cylinder coaxial with *a* and having one end thereof slightly overlapping the latter,—*c*, (Fig. 1) strips attaching pipe

a and cylinder *b* and formed so as to offer a minimum of resistance to the flow of fluids, elements *c* being replaced in Figs. 2 to 4 by radial supporting brackets *d*,—and *e*, a cap which varies with the particular application and which, in Figs. 1, 3 and 4, is made in the form of a flat disc supported on *b* either by strips *f* (Fig. 1) or radial vanes *g* (Fig. 2) lying preferably in the same plane as elements *c* and *d* respectively.

The dimensions and positions of *a* and *b* are so chosen that, if

D represents the interior diameter of *a* at its free extremity,

D_1 the interior diameter of *b*,

H the overall length of *b*,

H_1 the overlap of *b* over *a*,

$1.5D < D_1 < 2.5D$

$0.10H < H_1 < 0.30H$

$0.50D < H < D_1$

where the symbol $<$ indicates "is less than".

Similarly, if D_2 =the diameter of cap *e*, and H_2 =the distance between *e* and *b*, the following conditions should be substantially fulfilled:—

$$D_1 < D_2 < 3D_1$$

$$\frac{D_1}{2} < H_2 < 1.5D_1$$

If H_1 is given a predetermined value, e. g. 4 centimeters, a series of curves such as is represented in Fig. 9 may be determined for varying values of *D*. Assuming that it is desired to establish optimum values of *D* for each value of *H*, it is only necessary to plot

v^1

v^0

as ordinates (v^1 representing the velocity of the air in pipe *a* and v^0 the velocity of the exterior air) and heights *H* as abscissæ.

Figs. 1 to 3 show the invention applied to a chimney having a single outlet. In Fig. 4, main pipe *a* of the chimney is fitted with a plurality of branches *a*¹ forming an angle of any obliquity with *a*. If desired, *a* may be rotatably mounted, thus permitting branches *a*¹ to change position with the wind.

Fig. 5 illustrates the invention applied to

the rotation of a propeller h intended to furnish power. Here pipe a is mounted at right angles, and so as to project into aerodynamic chamber i . In this form of device cap e is unnecessary and is, therefore, eliminated. Fig. 6 merely shows that the invention is not limited to chimneys and the like carrying hot gases but may be applied equally well to a space containing air at the same temperature as the gas current producing the draft.

In applying the invention to an automobile or other closed moving vehicle, it is found that the direction of the ventilating current is never reversed and takes place always from the interior towards the exterior. Similarly, in lamp l shown in Fig. 8, the most violent gusts of wind fail to extinguished the flame.

Obviously, the invention is not limited to the particular devices hereinabove shown and described, but may be applied in a variety of other ways; thus either the primary or secondary currents may be liquid instead of gaseous or may carry liquid or solid particles in suspension. Similarly, pipe a and cylinder b may be given a polygonal or elliptical section or may take the form of any surface of revolution having, preferably, a portion thereof cylindrical; cap e may be conical (Fig. 2) or spherical or spiral; element a or b or e or all three may be made of perforated instead of solid material; the axis of element b may be out of line with the axis of a ; cylinders a and b may have the same diameter; etc., etc.

If element b is given some other shape than that of a cylinder and pipe a remains circular in section, the following relation should hold

$$D^3(D \text{ cubed}) < V < 5 D^3,$$

Where D =the diameter of the free extremity of a .

And V represents the volume of element b .

Similarly, whatever may be the form of section of pipe a or of element b , the following relations should be fulfilled.

$$2S < S_1 < 7S$$

$$\sqrt{\frac{S}{\pi}} < H < 2\sqrt{\frac{S}{\pi}}$$

$$S_1 < S_2 < 9S_1$$

$$\sqrt{\frac{S_1}{\pi}} < H_2 < 3\sqrt{\frac{S_1}{\pi}}$$

$$\left(\frac{S}{\pi}\right)^{3/2} < V < 5\left(\frac{S}{\pi}\right)^{3/2}$$

Where S =the area of a section taken at the free extremity of a .

S_1 =the area of a section taken at either extremity of b ,

S_2 =the area of a section taken at the free end of cap e (case where e is hemispherical, conical or other shape),

H =the length of b ,

H_2 =the distance separating b and e , and V =the volume of b .

Whatever may be the form of elements of a and b their sections should preferably have the values,

$$S_1 = 3.2 \text{ S.}$$

What I claim is:—

1. A device of the class described comprising a pipe having an extremity of diameter D , a cylindrical element having a diameter D_1 and a length H mounted on one end of said pipe so as to present an overlapping portion of a length H_1 , and a cap of diameter D_2 mounted at a distance H_2 from said cylindrical element, said dimensions D , D_1 , D_2 , H , H_1 and H_2 satisfying the relations

$$2D_1 \text{ is greater than } 3D \text{ and is less than } 5D$$

$$10H_1 \text{ is greater than } H \text{ and is less than } 3H$$

$$2H \text{ is greater than } D \text{ and is less than } 2D$$

$$2D_2 \text{ is greater than } 3D \text{ and is less than } 6D$$

$$4H_2 \text{ is greater than } 3D \text{ and is less than } 6D.$$

2. A device of the class described comprising a pipe having an extremity of diameter D , a cylindrical element having a diameter D_1 and a length H mounted on one end of said pipe so as to present an overlapping portion of a length H_1 , and a cap of diameter D_2 mounted at a distance H_2 from said cylindrical element, said dimensions D , D_1 , D_2 , H , H_1 and H_2 satisfying the relations

$$20D_1 \text{ is greater than } 33D \text{ and is less than } 38D$$

$$10H_1 \text{ is greater than } 2H \text{ and is less than } 3H$$

$$20H \text{ is greater than } 13D \text{ and is less than } 18D$$

$$4D_2 \text{ is greater than } 9D \text{ and is less than } 11D$$

$$8H_2 \text{ is greater than } 7D \text{ and is less than } 9D.$$

3. In a device of the class described, a pipe having an extremity of sectional area S , a hollow member of length H and volume V mounted on said pipe and presenting a section having an area S_1 , and a cap spaced at a distance H_2 from said hollow member and having an opening extremity of section S_2 , said dimensions S , S_1 , S_2 , H , H_2 and V lying within the limits defined by the following expressions: four times area S_1 is greater than nine times area S and is less than twenty-five times area S ; dimension H is greater than the radius of a circle having an area S and is less than twice the radius of a circle having an area S ; two times area S_2 is greater than two times area S_1 and is less than three times area S_1 ; twenty times dimension H_2 is greater than five times the radius of a circle having an area S_1 and is less than six times the radius of a circle having an area S_1 ; the volume V is greater than the volume of a cube having a side equal to the diameter of a circle having an area S and is less than five times the volume of a cube having a side equal to the diameter of a circle having an area S .

4. A device of the class described comprising a pipe having an extremity of diameter D , a cylindrical element having a diameter D_1 and a length H mounted on one end of

said pipe so as to present an overlapping portion of a length H_1 , and a cap of diameter D_2 mounted at a distance H_2 from said cylindrical element, said dimensions D , D_1 , D_2 , H , H_1 and H_2 satisfying the relations

5       $8D_1$ is equal to $15D$

$9H_1$ is equal to $2H$

$5H$ is equal to $4D$

$2D_2$ is equal to $5D$

H_2 is equal to D .

10   In testimony whereof I have hereunto set
    my hand.

CHRISTIAN COUPARD.
